[57] ABSTRACT

A dry cleaner, and an aqueous wig cleaning solution formed by adding the cleaner to water, characterized by critical concentrations; sufficient to effect detergentless cleaning and less than that adversely affecting the hairlike fiber and backing materials of the wig; of sodium chloride, sodium bicarbonate, and sodium hexametaphosphate. No other ingredients are necessary to effect a surprisingly good cleaning solution that is also remarkably and surprisingly effective in restoring and maintaining excellent quality and body in the wig materials.

INVENTOR

AGNES M. HUGHES

CLEANER FOR WIGS

BACKGROUND OF THE INVENTION

1. Field of the Invention:

This invention relates to cleaners, including cleaning solutions; and, more particularly, to detergentless cleaners for cleaning hairlike fiber and other constituents of wigs.

2. Description of the Prior Art:

The prior art is replete with diverse cleaners and cleaning solutions. There are increasing needs for specialty cleaners and cleaning solutions. For example, wigs with their hairlike fiber have become increasingly popular and most of the cleaning solutions employed heretofore have proven to have adverse effects that made them unsuitable for the wigs. For example, the detergents were so harsh that they dried the hair too severely for long life. To remove the natural oils that transferred from the wearer's hair to the wig, non-aqueous wig cleaning solutions were adverted to and proved satisfactory in cleaning the oils and the like from the wigs. These non-aqueous wig cleaning solutions, however, adversely affected the backing materials of which the wigs were made, particularly where the backing materials contained rubber-like materials. Even the sophisticated and expensive aqueous detergent-containing solutions and the nonaqueous, hydrocarbon-containing solutions have not satisfied the demand for a cleaner and a cleaning solution that would clean the oils from the wig and its materials, would maintain and restore body and luster to the hairlike fiber of the wig, and that would not adversely effect the materials of the wig. The term "hairlike fiber" is employed herein to include human hair, since wigs frequently include humane hair.

BRIEF DESCRIPTION OF THE DRAWINGS

The FIGURE is a three-component diagram illustrating the concentrations of the components which have been found critical, and optimum, in one embodiment of this invention.

fiber, may be washed therein. A particular advantage of the wig cleaning solution of this invention is that the wigs do not ordinarily require rinsing after they have been washed therein. I have found that surprisingly clean wigs are effected and the hairlike fiber of the wig has a remarkable sheen, brilliance and body following the use of the cleaning solution of this invention, in contrast to other available cleaning solutions employing detergents or hydrocarbon constituents. The wig may then be set in conventional fashion. The hairlike fiber is more manageable and easier to work with following cleaning with the cleaner of this invention than with other cleaners available.

In developing the cleaner, a wide variety of conditioning agents and detergents were employed. For reasons of cost and ready availability the sodium cation is the preferred alkali metal cation employed. It is recognized that chemically, other alkali metal cations such as potassium are equally efficacious. For much the same reason the chloride anion is the preferred halide anion. Similarly, it is recognized that chemically, other halide anions such as bromides and iodides may be satisfactory. The alkali metal halide chosen should not form insoluble precipitates with the constituents of the water, however. The alkali metal borax and phosphate water conditioning agents such as sodium borax and the sodium phosphates may be employed in forming a minimally satisfactory wig cleaning solution. The sodium hexametaphosphate has proven so surprisingly superior in conditioning the hair that I have turned to it in preference to the others. The glassy form is readily and economically available under the trade name Calgon. Table 1 summarizes the concentrations that I have delineated thus far as satisfactory. The concentrations are expressed in terms of the actual amounts of individual compounds that I was employing, and in terms of the percent by weight in the cleaning solution (wt. percent). They are divided into the minimum, optimum, and maximum concentrations found to be satisfactory.

SUMMARY OF THE INVENTION

It is an object of this invention to provide a dry cleaner and an aqueous wig cleaning solution employing the same that will obviate the disadvantages of the prior art cleaning solutions and will clean the hair oils from the wig and its components, will maintain and restore body and luster to the hairlike fiber of the wig, and will not adversely affect the components of the wig.

In accordance with this invention there is provided a dry cleaner in a form for dissolution in water to form an aqueous wig cleaning solution, and an aqueous wig cleaning solution employing same, consisting essentially of an alkali metal halide such as sodium chloride in a concentration sufficient to enhance the cleaning and conditioning of the hairlike fiber of the wig and less than that causing stripping of the hair; an alkali metal bicarbonate such as sodium bicarbonate in a concentration sufficient to enhance the cleaning and conditioning of the hairlike fiber of the wig and less than that causing drying so severe that the hairlike fiber loses its softness and luster; and an alkali metal water conditioning agent such as glassy sodium hexametaphosphate in a concentration sufficient to effect a cleaning and conditioning solution and less than that causing embrittlement and drying of the hairlike fiber and deleterious reaction with the backing material of the wig.

BRIEF DESCRIPTION OF PREFERRED EMBODIMENTS

In practicing the invention, an aqueous wig cleaning solution may be prepared directly by incorporating and dissolving the individual compounds directly into water. After the wig cleaning solution has been formed, the wig, with its hairlike

Sodium chloride was found to be necessary in a small concentration sufficient to enhance the cleaning and conditioning of the hairlike fiber of the wig, if a detergent was to be omitted. Sodium chloride must be present in a concentration less than that causing stripping of the hair, or causing the hair to lose its original color. The concentration of at least about 0.016 wt. percent of sodium chloride has been found necessary to obtain a satisfactory cleaning solution that will clean the oil from the hairlike fiber of the wig. The best concentration effected was about 0.14 wt. percent. Concentrations above about 0.55 wt. percent was found to cause stripping of hair for some unknown reason.

Similarly, the sodium bicarbonate has been found to be necessary in a concentration sufficient to enhance the cleaning and conditioning of the hairlike fiber of the wig by the cleaning solution. Too great a concentration of the sodium bicarbonate, however, causes drying of the hairlike fiber so severe that the hairlike fiber loses its softness and luster, and becomes so unmanageable that obtaining a good set is difficult and impractical. At least 0.10 wt. percent sodium bicarbonate must be employed to effect the satisfactory cleaning solution. The best cleaning solution is effected when about 0.41 wt. percent sodium bicarbonate is employed. At concentrations above about 1.65 wt. percent of sodium bicarbonate the hairlike fiber begins to lose its softness and luster.

The glassy sodium hexametaphosphate must be present in a concentration of at least about 1.64 wt. percent to obtain the desired conditioning and cleansing action. The best cleansing solution is effected when an optimum concentration of about 3.28 wt. percent of the glassy sodium hexametaphosphate is

employed. At concentrations greater than about 6.4 wt. percent, deleterious reactions that are not completely understood cause embrittlement and drying of the hairlike fiber and a shorter life of the backing material of the wig.

EXAMPLE I

In a specific example, I have tried various concentrations of the respective compounds in 4 gallons of water. Numerous washings, with wigs and with my own hair, have indicated the concentrations set forth in the Table I are the critical concentrations as far as I have been able to delineate. As can be seen from Table I, the indicated quantities of the respective compounds were added to 4 gallons of water to form the aqueous wig cleaning solution.

The wig cleaning solution described hereinbefore forms a particularly preferred embodiment of the invention, since the wig may be cleaned in this wig cleaning solution directly without any additional work in preparing the solution. The cleaner may be marketed in other forms, however, in order to save the shipping costs of the relatively large quantities of water. For example, aqueous syrups, or concentrated solutions, may be marketed in which a predetermined quantity, such as a cap full, of the syrup would be added to a predetermined quantity of water to form the wig cleaning solution. A dry cleaner consisting essentially of an admixture of the critical concentrations of the three ingredients may be marketed. The dry cleaner would be in a form such as powder, containing granules and crystals, or briquettes, for adding a predetermined amount of the cleaner to a predetermined quantity of water to form the syrup or the wig cleaning solution described hereinbefore. Any standard form of combining the dry ingredients into briquettes may be employed, such briquetting procedures are well known and need not be described in detail herein. The FIGURE illustrates, via a three-component diagram, the critical concentrations which have been delineated. Expressed otherwise, the concentrations of the ingredients in the dry admixture are illustrated in the Figure wherein the respective axes represent concentrations of 0-100 percent sodium chloride, 0-100 percent sodium bicarbonate, and 0-100 percent glassy sodium hexametaphosphate. Table II summarizes in tabular form the data included in the Figure.

TABLE II

Description	Concentration in Percent by Weight		
	Minimum Concentration	Optimum Concentration	Maximum Concentration
Sodium chloride	0.2	3.6	23.8
Sodium bicarbonate	1.4	10.8	50.0
Glassy sodium hexametaphosphate	27.2	85.6	98.4

Table II summarizes the minimum and maximum concentrations based on the worst possible combination in which the lowest concentration of a given constituent would be included with the highest concentration of the other two constituents; and conversely, wherein the greatest concentration of a given constituent would be included with the lowest concentration of the other two. I have found, however, that the following practical range of concentrations of the respective constituents produce a wig cleaning solution that is much better, particularly where human hair is cleaned, and that these intermediate ranges of concentration represent the limits that are practical in a marketable cleaner. These practical limits are summarized in Table III.

TABLE III

5	Description	Concentration in Percent by Weight		
		Minimum Practical	Optimum	Maximum Practical
5	Sodium chloride	0.5	3.6	12.0
10	sodium bicarbonate	3.0	10.8	32.0
10	Glassy sodium hexametaphosphate	56.0	85.6	97.5

As can be seen in the Figure, the parallelogram within the region defined by A, B, C, and D is the maximum limits for the critical concentrations that will be employed. For practical purposes, the limits are defined by the parallelogram E, F, G, and H, the optimum concentration being defined by the point J.

I am aware that the constituents individually have been employed heretofore in conjunction with detergents for cleaning purposes. I am also aware that the individual constituents are so commonplace that there is a danger of equating simplicity with obviousness. I do not know of any cleaning solution employed heretofore, however, that embodies the enumerated constituents in the critical concentrations that will effect the cleaning, yet prevent the adverse effects, as delineated hereinbefore. While economically advantageous compounds have been specifically delineated herein, their chemical equivalents, as noted hereinbefore, are within the purview of this invention. It will be apparent that small concentrations of other additives may be employed as long as the other additives do not deleteriously effect the components of the wig or adversely affect the cleaning and conditioning properties of the wig cleaner or the wig cleaning solution. Because the respective compounds are so commonplace, I have employed claim language which requires that at least the three elements be employed in these critical concentrations for the purpose of cleaning wigs or wig constituents such as human hair.

What is claimed is:

1. A cleaning composition to enhance the cleaning and conditioning of the hairlike fiber of wigs, said composition consisting essentially of an aqueous solution containing:
  - a. an alkali metal halide in a concentration within the range of 0.016 to 0.55 percent by weight, inclusive;
  - b. an alkali metal bicarbonate in a concentration within the range of 0.10 to 1.65 percent by weight, inclusive; and
  - c. an alkali metal hexametaphosphate in a concentration within the range of 1.64 to 6.4 percent by weight, inclusive.
2. The wig cleaning solution of claim 1 wherein said alkali metal halide is sodium chloride, said alkali metal bicarbonate is sodium bicarbonate, and said alkali metal water conditioning agent is sodium hexametaphosphate.
3. The wig cleaning solution of claim 1 wherein said wig cleaning solution contains about 0.14 percent by weight sodium chloride, about 0.41 percent by weight sodium bicarbonate, and about 3.28 percent by weight of sodium hexametaphosphate.
4. A cleaner for forming a wig cleaning solution when added to water, consisting essentially of an admixture of:
  - a. an alkali metal halide in a proportion within the range of 0.2-23.8 percent by weight, inclusive;
  - b. an alkali metal bicarbonate in a proportion within the range of 1.4-50 percent by weight, inclusive; and
  - c. an alkali metal hexametaphosphate in a proportion within the range of 27.2-98.4 percent by weight, inclusive;
 said dry cleaner being in a form that will readily dissolve in water.
5. The cleaner of claim 4 wherein said alkali metal halide is sodium chloride, said alkali metal bicarbonate is sodium bicarbonate, and said alkali metal hexametaphosphate is sodium hexametaphosphate.
6. The cleaner of claim 5 wherein said sodium chloride is present in a concentration within the range of 0.5-12 percent

by weight, inclusive; said sodium bicarbonate is present in a concentration within the range of 3-32 percent by weight, inclusive; and said sodium hexametaphosphate is present in a concentration within the range of 56-97.5 percent by weight, inclusive.

7. The cleaner of claim 6 wherein said admixture is in a powdered form containing granules and crystals.

8. The cleaner of claim 6 wherein said admixture is in the form of briquettes.

9. The cleaner of claim 6 wherein said cleaner contains an optimum concentration in percent by weight of about 3.6 percent sodium chloride, about 10.8 percent sodium bicarbonate, and about 85.6 percent of sodium hexametaphosphate.
